UNITED STATES PATENT OFFICE.

FRANKLIN L. BARBER AND EDWIN W. WEBB, OF CHICAGO, ILLINOIS, ASSIGNEES TO
STANDARD CAR TRUCK COMPANY, OF CHICAGO, ILLINOIS, A CORPORATION OF NEW
JERSEY.

CAR-TRUCK.

1,240,166.

Specification of Letters Patent. Patented Sept. 18, 1917.

Application filed May 3, 1917. Serial No. 166,241.

To all whom it may concern:

Be it known that we, FRANKLIN L. BARBER and EDWIN W. WEBB, citizens of the United States, residing at Chicago, in the county of Cook and State of Illinois, have invented certain new and useful Improvements in Car-Trucks; and we do hereby declare the following to be a full, clear, and exact description of the invention, such as will enable others skilled in the art to which it appertains to make and use the same.

Our invention relates to improvements in car trucks, and particularly to six wheeled equalized passenger car trucks.

15 To the above end, generally stated, the invention consists of the novel devices and combinations of devices hereinafter described and defined in the claims.

In the accompanying drawings, which 20 illustrate the invention, like characters indicate like parts throughout the several views:

Referring to the drawings:

Figure 1 is a fragmentary plan view of 25 the improved car truck;

Fig. 2 is a view partly in side elevation and partly in longitudinal central section;

Fig. 3 is a transverse vertical section taken on the irregular line 3-3 of Fig. 1;

30 Fig. 4 is a detail view partly in elevation and partly in vertical section taken on the line 4-4 of Fig. 1; and

Fig. 5 is a detail view partly in elevation and partly in vertical section taken on the 35 line 5-5 of Fig. 4.

The truck frame, as shown, is made partly of cast steel and partly of rolled sections riveted together, but, as far as our present invention is concerned, it may be 40 cast entirely in one piece. Each side frame of the improved car truck is indicated by the numeral 6 and has rigidly bolted thereto, integrally formed pairs of pedestals 7. Between the members of each pair of pedestals 7 is mounted a journal box 8, with 45 freedom for vertical movement. The lower ends of the several pedestals 7, of each side frame 6, are rigidly connected by a flat tie-bar 9. These tie-bars 9 are laid in notches formed in the lower ends of the pedestals 7 and riveted thereto. Outward of the outer 50 pedestals 7, the tie-bars 9 are bent upward and riveted to the side frames 6 and between the several pairs of pedestals 7, said tie bars are twisted to turn the same on

edge. The wheels and axles of the improved car truck are indicated by the numerals 10 and 11, respectively.

The two side frames 6 are rigidly connected by end members 12 riveted thereto. Said side frames 6 are further connected by four transoms 13 also riveted thereto, arranged in laterally spaced pairs and located between the outer and intermediate journal boxes 8. The outer of these transoms 13 are rigidly connected to the adjacent end members 12 of the truck frame by a pair of tie-bars 14 secured thereto by rivets and gusset plates. The two intermediate transoms 13 are rigidly connected by a pair of tie-bars 15 riveted thereto. For a purpose that will presently appear, the central portions of the intermediate transoms 13 are dropped and the tie-bars 15 are supported on these dropped portions and against the shoulders formed therein.

The members of a double truck bolster 16 are located, one member between each pair of transoms 13 and said members are rigidly connected by an H-shaped casting 17 bolted thereto and carrying a center bearing plate 18. By reference to Fig. 2 it will be noted that the H-shaped casting 17 extends over the dropped portions of the intermediate transoms 13 and there is sufficient clearance therebetween to permit free vertical movement of the truck bolster 16. The ends of the members of the truck bolster 16 project under and outward of the side frames 6 and are further rigidly connected by side bearing arch bars 19 bolted thereto.

The double truck bolster 16 is indirectly supported from the truck frame by U-shaped hangers 21 and through which 95 hangers the ends of said bolster project.

These hangers 21 are suspended between the members of each pair of transoms 13 by flat keys 22 and are located in the same vertical plane with the wheels 10 on the respective sides of the truck frame. The ends of the hangers 21 are mounted in bearings 23 and their intermediate portions extend through hubs 24 formed on the upper ends of the hangers 21. The keys 22 are turned 100 edgewise and their upper and lower edge portions are rounded and fit correspondingly formed seats in the bearings 23 and hubs 24. Obviously, the keys 22, owing to their transverse shape, are held in the bearings 23 110

against turning movement and in turn hold the hangers 21 against swinging movement. The bearings 23 rest on the tops of the transoms 13 and are riveted thereto. Pins 25 inserted into alined seats in the keys 21 and bearings 23, hold said keys against endwise displacement. By the use of the hangers 21 it is possible to eliminate the customary spring planks.

10 Wearing plates 26 for the truck bolster 16, which take the place of the usual truck columns, are mounted in channel-like seats 27 formed vertically through the opposing faces of each pair of transoms 13. Nut-equipped bolts 28 rigidly but detachably secure the wearing plates 26 to the transoms 13. Formed in the side walls of the seats 27 are long vertical notches 29 which receive relatively short lugs 30 on the wearing plates 26 and assist in securing the same in position in said seats. In the backs of the wearing plates 26 are vertical channels 31 through which the vertical portions of the hangers 21 extend. By means of these channels 31 the hangers 21 are further and securely held against swinging movement transversely of the car truck. The lower ends of the hangers 21 are contracted and to afford clearance therefor, the lower ends of the wearing plates 26 are bifurcated.

15 The truck bolster 16 is supported from the hangers 21 and, hence, from the truck frame by elliptical springs 32 and lateral motion rollers 33. The springs 32 extend 35 transversely, with respect to the truck frame, and rest upon spring seat 34 in the form of castings mounted on the horizontal portions of the hangers 21. Laterally spaced lugs 35 on the ends of the spring seat 34 engage opposite edge portions of the hangers 21 and hold said seats thereon against lateral displacement. On top of each elliptical spring 32 is supported a roller base 36 having contours to receive the rollers 33. The truck 40 bolster 16 rests directly upon the lateral motion rollers 33 and has formed in its under side contours 37 to receive said rollers. On the ends of the roller bases 36 is a pair of laterally spaced guide lugs 38 arranged to 45 receive the wearing plates 26 and coöperate therewith to hold said roller bases against lateral displacement, but with freedom for vertical movement.

50 Stop lugs 39 on the sides of the truck bolster 16 are arranged to engage the wearing plate 26, under extreme lateral movement of the truck bolster 16 and limit said movement.

55 Equalizing bars 40 have their outer ends supported on the outer journal boxes 8 and their inner ends supported on the intermediate journal boxes 8. These equalizing bars 40 are dropped, between the journal boxes 8, into substantially the same horizontal 60 plane with the tie-bars 9 and arranged sub-

stantially parallel therewith. The truck frame is supported from the equalizing bars 40 and hence from the journal boxes 8 by coiled springs 41. These springs 41 are mounted on spring bases 42, supported on the equalizing bars 40 and their upper ends are mounted in spring caps 43 integrally formed with the outer transoms 13 and located directly under the side frames 6.

65 From the above description, it is evident that the load of the car is directly on the double truck bolster and it, in turn, is supported from the truck frame by lateral motion bearing devices and elliptical springs. The weight on the truck frame is applied 70 to the journal boxes through the coiled spring and equalizing bars. By the construction and arrangement of the parts just referred to, each wheel is allowed to move vertically and independently of the others 75 thereof.

80 What we claim is:

1. In a car truck, the combination with a frame and a bolster, of bolster hangers, and keys supporting said hangers from the 85 frame and holding the same against swinging movement.

2. In a car truck, the combination with a frame and a bolster, of bolster hangers, and flat keys supporting said hangers from 90 the frame and holding the same against swinging movement.

3. In a car truck, the combination with a frame and a bolster, of bolster hangers carried by the frame, and wearing plates 100 on the frame arranged to hold said hangers stationary and affording bolster columns.

4. In a car truck, the combination with a frame and a bolster, of stationary bolster hangers carried by the frame, and springs 105 and lateral motion bearing devices supporting the bolster from said hangers.

5. In a car truck, the combination with a frame and a bolster, of stationary bolster hangers carried by the frame, wearing plates 110 assembled in connection with said hangers and affording bolster columns, and springs supporting the bolster from said hangers.

6. In a car truck, the combination with a frame and a bolster, of bolster hangers 115 carried by the frame, wearing plates on the frame, arranged to hold said hangers stationary and affording bolster columns, and springs supporting the bolster from said hangers.

7. In a car truck, the combination with a frame and a bolster, of U-shaped bolster hangers carried by the frame, wearing plates on the frame having channels to receive the side members of said hangers and thereby hold said hangers stationary, said wearing plates affording bolster columns, and springs supporting the bolster from the transverse portions of said hangers.

8. In a car truck, the combination with 130

a frame and a bolster, of U-shaped bolster hangers carried by the frame, wearing plates on the frame and affording bolster columns, spring seats carried by the transverse portions of said hangers, elliptical springs mounted in said spring seats, and lateral motion bearing devices interposed between the bolster and springs and including roller bases having guide lugs coöperating with said wearing plates.

9. In a car truck, the combination with a frame and a bolster, of U-shaped bolster hangers, keys supporting said hangers from the frame and holding the same against swinging movement, and springs supporting the bolster from said hangers.

10. In a car truck, the combination with side frames, a pair of laterally spaced transoms connecting the same and a bolster, of U-shaped bolster hangers, keys mounted in bearings on the transoms and supporting said hangers, said keys being rigidly held in their bearings and in turn holding said hangers against swinging movement, and springs supporting the bolster from said hangers.

11. In a car truck, the combination with a frame, a bolster and journal boxes, of equalizing bars supported from the journal boxes, bolster hangers carried by the frame, springs and lateral motion bearing

devices supporting the bolster from the hangers, and springs supporting the frame from the equalizing bars.

12. In a car truck, the combination with side frames and independent transoms connecting the same and having integrally formed spring caps on which said side frames rest, of journal boxes, equalizing bars carried by the journal boxes and having spring bases, and springs mounted on said spring bases and spring caps and supporting the side frames from the equalizing bars.

13. In a car truck, the combination with side frames and independent transoms connecting the same and having integrally formed springs, caps on which said side frames rest, of journal boxes, equalizing bars carried by the journal boxes and having spring bases, and springs mounted on said spring bases and spring caps and supporting the side frames from the equalizing bars.

In testimony whereof we affix our signatures in presence of two witnesses.

FRANKLIN L. BARBER.
EDWIN W. WEBB.
